UNITED STATES PATENT OFFICE.

LEE DE FOREST, OF NEW YORK, N. Y., ASSIGNOR TO DE FOREST RADIO TELEPHONE & TELEGRAPH COMPANY, A CORPORATION OF DELAWARE.

ARC MECHANISM FOR SYSTEMS OF SPACE COMMUNICATIONS.

1,123,120.

Specification of Letters Patent. Patented Dec. 29, 1914.

Application filed January 20, 1909. Serial No. 473,316.

To all whom it may concern:

Be it known that I, LEE DE FOREST, a citizen of the United States, residing at New York, in the county and State of New York, have made a certain new and useful Invention in Arc Mechanism for Systems of Space Communications, of which the following is a specification.

This invention relates more particularly to the arc mechanism employed in connection with systems of space communication.

The object of the invention is to provide means which are simple and efficient for maintaining a low voltage arc in the production of electro-magnetic oscillations and the radiation of wave trains therefrom.

A further object is the provision of means whereby the arc may be readily and easily controlled, and the electrodes maintained cool, thereby utilizing, to the greatest possible extent, the energy supplied to the arc, in the generation and radiation of the wave trains.

Other objects of the invention will appear more fully hereinafter.

The invention consists substantially in the construction, combination, location, and arrangement, all as will be more fully hereinafter set forth, as shown in the accompanying drawings, and finally pointed out in the appended claims.

In the accompanying drawings, Figure 1 is a view showing one form of mechanism and arrangement embodying the principles of my invention, and designed for radio or space telephonic use. Fig. 2 is a view illustrating another method of controlling the arc for radio or space telephonic communication. Fig. 3 is a view illustrating an arrangement designed for radio or space telegraphic operation. Fig. 4 is a view showing a form of means for regulating the space between the electrodes.

In the operation of apparatus employed for effecting communication through space it is exceedingly desirable to utilize to the greatest possible extent the energy employed in the generation of the electro-magnetic wave trains, since the greater the efficiency in wave train generation, as compared with the primary energy employed, the greater will be the distances through which communication can be effected, and the closer and sharper can the system be

tuned. In systems heretofore proposed, and, particularly systems employing an electric arc bridged by an oscillating circuit containing a condenser and self induction, a large part of the energy of the current employed to produce the arc is consumed in the heat of the arc and in heating the electrodes and adjacent parts, thereby detracting from the energy of the radiations produced. Various expedients have been proposed for overcoming this difficulty, by employing a hollow electrode and circulating a cooling medium therethrough, by forming the arc in air, and the like, but these methods have proven only partially successful in attaining the desired results. Moreover, in arc systems heretofore employed it has been necessary to bring the electrodes into contact with each other, and then to separate them in order to strike the arc. In the case of relatively moving electrodes this is objectionable since one or the other of the relatively moving electrodes is worn or broken off on the surface thereof at the point of contact, and in any event the length of the arc is varied, thereby introducing irregularities into the operation of the system, and requiring constant adjustments of the parts to overcome them.

It is among the special purposes of my present invention to obviate these and other objections encountered in the use and operation of apparatus of this nature, and to provide means whereby the greatest possible amount of the energy employed in the arc circuit is utilized in wave train generation, whereby physical contact of the arc electrodes is avoided, whereby the arc is struck and is maintained without the electrodes being brought into contact with each other, whereby the arc as well as the adjacent parts, is maintained cooled and whereby efficient control of the arc is effected and maintained.

In carrying out my invention I employ electrodes which are relatively movable, and also capable of adjustment toward and from each other, the arc being formed between the proximate relatively moving edges or surfaces of the electrodes and I deliver a jet or spray of liquid upon the arc and upon the surfaces of the electrodes at and adjacent the arc. The jet or spray forms a film which bridges the space between the elec-

trodes and strikes the arc, and thereafter maintains the electrodes cool and reduces the heat of the arc, thereby enabling a large part of energy which has heretofore been 5 dissipated in heat, to be utilized in the production of oscillations for generation and radiation of electro-magnetic wave trains.

In the drawings, reference signs e' , e^2 , designate electrodes. These may be of any 10 suitable or convenient construction and arrangement. In practice, however, I prefer to employ metallic electrodes. In the form shown in Fig. 1, the electrodes e' , e^2 , are mounted for relative movement, and, in this 15 instance, the electrode e^2 , is in the form of a disk mounted to revolve on its axis, while the electrode e' is cylindrical in form and is supported in such relation to the disk electrode e^2 as to present one edge thereof to 20 the edge of the revolving disk. The electrodes e' , e^2 , are inclosed within a casing D, which opens or delivers into a receptacle F. A fine jet or spray of a suitable fluid, such for instance, as water, is delivered upon the 25 arc formed between the proximate points of the electrodes, as, for example, through a nozzle N, extending into the casing D, from a supply reservoir R'. A valve, cock or other convenient throttling device k, may serve to 30 regulate and control the jet or spray delivered to the arc. The fluid, after performing its function, at and in the vicinity of the arc, passes from the casing D, into the receiving receptacle F, or elsewhere, as may be convenient, and, if desired may, be returned to 35 the reservoir R', by means of a pump P, or other means. The circuit of the arc electrodes is supplied with energizing current from any suitable or convenient source. I 40 have shown a direct current generator G, for this purpose. The circuit of the arc is bridged by an oscillating circuit containing a self inductance L', and a condenser C. The oscillating circuit may be associated, in 45 any desired or well known manner, with the circuit of an aerial or antenna A, which may be grounded as at E. In the form shown the inductance L' of the oscillating circuit is inductively associated with an inductance L², in the antenna circuit, although other forms of association or coupling of the oscillating and antenna circuits may be employed. The oscillations in the oscillating 50 circuit, or those set up in the antenna circuit, may be modified in any well known manner for the purpose of effecting the desired communication, as, for instance by means of a microphone, indicated at M, or otherwise, as may be desired. A desirable 55 relative adjustment of the electrodes, the one toward or away from the other, may be accomplished in any suitable or convenient manner in order to adjustably regulate the length of the arc. In Fig. 4, I have shown 60 a simple and efficient arrangement for ac-

complishing this result, and wherein the electrode e' , is carried loosely in a rotatable sleeve or holder B', and is supported upon the bent end b', of an adjustable rod b². The adjusting nut b³ serves to adjust the rod b², thereby adjustably regulating the space between the proximate edges of the electrodes at the points where the arc is produced and maintained. 70

Instead of delivering a jet of water or other fluid upon the arc, such fluid may be delivered thereto in proper form in many other ways. In Fig. 4, I have indicated how a spray of the fluid may be delivered to the arc by the rotation of the electrode e^2 , in the fluid contained in the casing D', the rapidly revolving electrode operating to carry a sufficient amount of the fluid around with it to cause a spray or film of the liquid to be delivered upon the arc. In this case the casing D', is closed and contains a sufficient amount of the fluid for the electrode e^2 , or a portion thereof, to revolve in such fluid. 75 80 85

I have found that the oscillations of the arc depend so materially on the delivery of the fluid jet, film or spray, thereto, that they become completely interrupted, and the arc may become completely extinguished when the jet, film or spray is cut off or arrested. I may make use of this, therefore, in effecting space communication, by suitably regulating, varying or otherwise controlling the supply or delivery of the jet, film or spray of liquid to the arc. This control of the jet, and by this term herein I intend to include 90 a film or spray, may be effected by means of a quick acting valve or cock, k, through the proper manipulation of which, in place of a telegraph key, for instance, radiations corresponding to and capable of being received at the distant station as, dots and dashes of the Morse telegraph code, may be produced, thereby dispensing with the necessity for a telegraph key. Similarly, for 95 telephonic communication, the jet may be varied or controlled, or its path altered or changed by suitable means, such, for instance, as a deflector, pin, vane or other convenient form of throttling or controlling device, arranged to be operated by the sound waves produced by articulate speech, as, for instance a diaphragm M, having a mouth-piece M', for directing the sound waves produced by the voice to such diaphragm. In 100 Fig. 2 is shown an arrangement embodying this idea, the dotted line p', indicating the normal path of the jet, said jet being more or less deflected from such normal path by the operation of the pin or vane p, according 105 to and in consonance with the vibrations of the diaphragm m. In this way much larger currents can be controlled by the voice sounds, and a greater range of transmission 110 accomplished, than has heretofore been possible in systems of this nature. 115 120 125 130

The construction and arrangement of the electrode e^2 , shown in Figs. 1, 2 and 4, is particularly designed for use in connection with telephonic communication, as, thereby, 5 continuous wave-trains are radiated. In the form shown in these views of the drawing, this electrode comprises a disk mounted to revolve in such relation to the electrode e' , as to present its rotating edge to the 10 proximate point or edge of the electrode e' , the arc being formed between the points on the edge surfaces of the electrodes which are in closest approximation to each other, and as the arc is constantly maintained, at 15 least so long as the jet of water or other fluid is supplied thereto, it will at once be perceived that continuous wave train radiations are effected, as above stated, this being a desired condition for space telephonic communication. 20 In the case of wireless or space telegraphic work, however, I propose to employ an electrode having its peripheral edge toothed, or formed irregularly in any arbitrary form, depending on the tone or 25 timbre of the note which it may be desired to use at the receiving station. This arrangement is shown in Fig. 3, and by such arrangement, the jet, spray or film of water or other fluid, being maintained, as above 30 explained, the arc is successively established between the teeth of the one electrode and the proximate point of the other, or between the teeth of both electrodes, if both are toothed, as the electrodes, or the toothed surface thereof are relatively moved, the arc being successively extinguished as the teeth 35 pass in such relative movement. In this manner the arc is rapidly made and extinguished, and in the desired degree of 40 rapidity to produce the required note in the receiver. The result is that a rapid succession of long, slowly damped wave trains are generated and radiated, thus giving all the 45 advantages of exceedingly sharp tuning or syntony, while at the same time producing a high frequency note at the receiver, very 50 easy to distinguish and read. The key K, may be placed at any desired or convenient part of the system, in the usual or any well known manner. In all cases it is desirable 55 to maintain the electrodes out of physical contact with each other. The jet, spray or film of water streaming across the gap between the proximate points of the electrodes 60 and over the surfaces of the electrodes not only maintains the arc and electrodes cool, even when a current of high amperage, say ten amperes, is employed, but it also serves to bridge such gap, thereby establishing the 65 arc without requiring the electrodes to be brought into physical contact with each other. Thus I am enabled to employ a current of large amperage and comparatively low voltage, securing very violent and regular oscillations, thereby greatly extending

the range of distance through which the apparatus is effective for communication, and by merely changing from the disk to the tooth form of electrodes, I am enabled to vary from a constant arc, giving continuous 70 wave train radiation, such as is desirable to employ for telephonic operation, to an interrupted arc, giving a rapid succession of long, slowly damped wave train radiations, such as is desirable for telegraphic work. 75

Many different arrangements and forms of electrodes may be employed, and many different arrangements of other details may be adopted and still fall within the spirit and scope of my invention as defined in the 80 claims. I do not desire, therefore, to be limited or restricted to the exact or any specific form and arrangement of apparatus. But

Having now set forth the object and nature of my invention, and various arrangements and embodying the principles thereof, what I claim as new and useful and of my own invention, and desire to secure by Letters Patent is:

1. The combination with arc electrodes having an air space between their proximate portions, of means for causing a continuous flow of liquid to the air space between the electrodes. 90

2. In an apparatus for wireless communication including a radiating system, the combination with arc electrodes, of means for continuously delivering a liquid jet to the space between said electrodes, and means for controlling said jet. 95

3. In an apparatus for wireless communication, an oscillating system including arc electrodes arranged out of contact with each other, with an air space between their proximate portions, of means for continuously delivering a liquid jet to the air space between said electrodes. 100

4. In an apparatus for wireless communication, an oscillating system, including arc electrodes, means for maintaining said electrodes out of physical contact with each other, with an air space between their proximate portions, and means for continuously delivering a liquid to the air space between the electrodes. 110

5. The combination with arc electrodes, of means for playing a jet of water on the proximate surfaces of said electrodes.

6. The combination with arc electrodes mounted for relative movement, of means for adjusting the same toward and from each other, and means for delivering a liquid jet to the space between said electrodes. 120

7. An apparatus for wireless communication including arc electrodes, means for rotating one of said electrodes, and means for delivering a jet of water to the space between said electrodes. 125

8. An apparatus for wireless communica- 130

- tion including arc electrodes, means for rotating both of said electrodes, and means for delivering a jet of water to the space between said electrodes. 35
5. 9. An apparatus for wireless communication including arc electrodes one of said electrodes being a disk mounted for rotation, and means for supplying a jet of cooling liquid to the space between the electrodes. 40
10. 10. An apparatus for wireless communication including arc electrodes mounted for relative movement, and a nozzle arranged to deliver a jet of cooling liquid to the space 45 between the electrodes.
11. An apparatus for wireless communication including arc electrodes spaced apart with an air space between them and mounted for relative rotation, one of said electrodes having means to successively interrupt the arc, and means for causing a continuous flow of liquid to the air space between the electrodes. 50
20. 12. An apparatus for wireless communication including arc electrodes spaced apart with an air space between them mounted for relative rotation, one of said electrodes being toothed, and means for causing a continuous flow of liquid to the space between 55 said electrodes.
25. 13. An apparatus for wireless communication including arc electrodes mounted for relative rotation, one of said electrodes being toothed, and means for supplying a cooling
15. liquid jet to the space between said electrodes. 55
14. An apparatus for wireless communication including arc electrodes mounted for relative movement, one of said electrodes being in the form of a toothed disk, and means for continuously supplying a jet of liquid to the space between said electrodes. 60
15. An apparatus for wireless communication including arc electrodes, means for continuously delivering a jet of liquid to the space therebetween, and means for controlling said jet. 65
16. An apparatus for wireless communication including arc electrodes mounted for relative movement, means for continuously delivering a jet of liquid to the space between the electrodes, and means for controlling said jet. 70
17. An apparatus for wireless communication including arc electrodes mounted for adjustment the one toward the other, means for continuously delivering a jet of liquid to the space between said electrodes, and means for controlling said jet. 75
- In testimony whereof I have hereunto set my hand in the presence of the subscribing witnesses, on this 18th day of January A. D., 1909. 80
